CONNECTOR LUG STRUCTURE

Frank C. Ebert, Richmond Hill, N. Y., assignor
to Allied Control Company, Inc., New York
County, N. Y., a corporation of New York

Application August 7, 1942, Serial No. 453,983

2 Claims. (Cl. 173—324)

The present invention is directed to electrical devices, and more particularly, to terminal elements or connector structures constituting a part of such electrical devices.

Various devices of this type, such as switches and relays, have metallic terminal members to facilitate the making of the necessary electrical connections between the devices and the sources of power or the ultimate operating apparatus. Such connector structures have been of various types, as for example, in one such device of the prior art, a screw-threaded member was inserted into a suitable base or block and held by various means. Such a structure required a considerable amount of assembly, so that it was not fully adapted to quantity production in a continuous line system. Also, such terminal members being based upon a threaded device, were subject to loosening and loss due to vibration to which the electrical device is often subjected.

Another type of connector structure which had previously been used consisted in one or more flat metallic members which were punched from sheet material and, by dies, bent into various shapes. Such connectors were then secured to a base, usually by threaded members or by rivets. Such a connector structure had a number of disadvantages, particularly in that a considerable number of operations were necessary and the assembly was awkward, so as to make it difficult to conduct the operations in an assembly system.

Very often, it was necessary that a connector be capable of having more than one wire secured thereto and this introduced additional complications in prior connector structures. Such complications still further decreased the possibility of using the old structures in a line assembly system.

The present invention is intended and adapted to overcome the difficulties and disadvantages of prior connector structures and to provide a device which is extremely simple in construction, which may be readily assembled with but very few operations, which will provide a connector firmly in place and incapable of loosening through vibration.

It is still further among the objects of the present invention to provide a structure which does not require any cutting or machining or bending or dieing operations, and wherein the connector although firmly in place, may be readily removed when desired, without disturbing the remainder of the electrical apparatus.

In practicing the present invention there is provided a base member which is usually of

molded or fabricated insulating material and formed therein is a suitable opening which passes through the same. This opening is substantially rectangular in cross-section. In a specific embodiment of the invention, instead of providing but a single rectangular opening, two such openings at right angles to each other and forming a cross, are provided.

There is also provided a flat metal member, 10 relatively thin in cross-section, which may be punched or die from a sheet and which constitutes a connector lug. This lug has a relatively long central portion, the width of which is approximately the length of the opening in the insulating member. At one end thereof a shoulder is provided so that the width of the lug at said end is centrally greater than the length of said opening, so as to be capable of being firmly seated on the surface of the insulating member. 15 One or both ends of the lug are provided with recesses or notches adapted to accommodate a wire to be soldered or welded thereto.

The lug is made of a metal having sufficient resiliency so that it retains a bend made therein. 20 The lug is bowed or bent on a relatively long radius, so that when viewed from an edge, is an arc of a circle.

In order to provide a complete connector, two such lugs are taken and they are placed so that 25 the shoulder of one is opposite to the shoulder of the other, and the two lugs when held together have their meeting faces concave to each other. While held in such position, one of the lugs is inserted through the upper surface of the insulating member and the other is inserted through the lower surface of said member until the shoulders touch the respective surfaces. Due to the 30 springiness of the metal and the fact that the width of the opening is approximately the width of the two lugs when completely face to face, there is pressure exerted against the walls of the opening which firmly hold the lugs in place.

In some cases it is not essential that the two connector elements or lugs be bowed so as to be held by tension in the insulating member. For 35 instance if the opening or slot in the insulating member is sufficiently narrow, the two connector lugs will be held by friction against the walls of said insulating member. Even if the slot is wider, the lugs may be positioned therein without friction, and then secured in fixed relation to each other. In such cases the lugs need not be made of metal which has resiliency, but soft metal lugs are fully suitable.

Also it is not necessary that both lugs be bowed

as the bowing of one of the lugs will often be sufficient to hold the parts in place. The bowed portions may have other shapes to give the necessary effect. One or both of the lugs may be corrugated or crimped to give the desired effect. Such curvatures may be longitudinal of the lugs or they may be transverse or in an intermediate position, just so that the distortion will be sufficient to give the springiness in the combination.

The essence of the invention is the provision of two connector lugs each having a shoulder and so placed that each shoulder engages an abutment, with the result that when they are secured together, they are firmly held in place. They may be joined by various means as by riveting, soldering, brazing and the like, or by the use of clips or other devices of such character; or the assembled lugs may be punched together or distorted locally to join them, or wire ties may be used. The lead-in wires may be inserted into the notches and said wires soldered without disturbing the alinement. As the result of the soldering the lugs are permanently fixed in place on the insulating member without any possibility of vibration loosening the same.

In the accompanying drawing constituting a part hereof and in which like reference characters indicate like parts:

Fig. 1 is a side elevational view of a relay embodying the connector structure of the present invention;

Fig. 2 is a top plan view thereof;

Fig. 3 is a plan view of one of the lugs entering into the connector structure;

Fig. 4 is an edge view showing two of the lugs in proper position for assembly; and

Fig. 5 is a fragmentary vertical cross-sectional view taken along the line 5—5 of Fig. 2.

The relay consists essentially of a magnetic circuit 1, a coil 2 therein held by screw 3. A molded insulating member 4 secured to the top 5 of the magnetic circuit has ears 6 bent therefrom, forming a hinge. An L-shaped armature 7 is hinged at 6 and has an insulating member 8 secured to the top thereof. Contact arms 9 are held on member 8 and wires 10 are welded thereto. On insulating member 4 are terminals 11 and 12.

Terminal lugs 13 are set in insulating member 4 and have wires 14 and 15 soldered thereto. Wires 14 may be connected to wires 10 and wires 15 may be connected to coil 2.

In insulating member 4 are formed a number of openings 16 passing therethrough. As shown in Fig. 2, such openings are relatively narrow and long and two such openings cross centrally of each other so that the openings are cruciform.

The terminal members each consists of a flat plate 17 having a notch 18 formed at one end thereof and a shoulder 19 adjacent the opposite end. At said opposite end is a notch or opening 20. The lug is bowed, as shown at 21 in Fig. 4. A similar lug has at the narrow portion 22 there-of an opening 23 corresponding to opening 18 of Fig. 3 and a shoulder 24 corresponding to shoulder 19 of Fig. 3, and a notch 25 corresponding to notch 20 of Fig. 3.

In assembling the terminal structure, lug 17 of Fig. 3 is introduced into slot 16 of Fig. 2 and pressed downwardly until shoulder 19 contacts with the upper surface of insulating member 4. Then the other lug is pushed upwardly in said opening until shoulder 24 abuts against the un-

der-surface of insulating member 4. Thereby, notches 20 and 23 become alined and notches 18 and 25 become similarly alined. A wire 14 is introduced into notches 18—25 and is soldered in place. This permanently unites the two lugs and holds them firmly in place. Another wire may be introduced into notches 20—23 and similarly soldered.

As will be seen from the above description, the labor necessary in making and assembling the connector structure is extremely small. The openings in the insulating plate are made automatically during the molding operation and require no additional labor. There is but one metal piece which can be stamped out automatically from strips or sheets of material and the bend or bow therein may be made automatically in the die during the operation. The assembly consists merely in slipping two pieces into an opening. Such a construction lends itself admirably to quantity production at a very low cost, while serving the purpose of making a terminal in an ideal manner.

It is, of course, understood that the invention is capable of being applied in various physical forms and that the exact form shown in Fig. 3 of the lug is only illustrative of the many forms which may be used. Various metals are adaptable for the purpose, it being desirable, however, that the metal have sufficient springiness so as to be held in place temporarily by friction, prior to the soldering operation. Although as shown, the terminal structure is applied to a relay, it is, of course, obvious that it may be used in all types of electrical structures requiring such terminals. Also, it is not necessary that the terminal be adapted for the attachment of wires at more than one point, as is apparent.

These and other changes in the details of construction of the invention may be made within the spirit thereof. The invention is to be broadly construed and not to be limited, except by the character of the claims appended hereto.

I claim:

1. In combination, an insulating member having an opening therethrough of substantially rectangular cross-section, a pair of metal strips passing through said opening, a shoulder on each strip, the shoulder of one strip contacting the surface of said member at one end of said opening and the shoulder of the other strip contacting said member at the remaining end of said opening, at least one of said strips being resilient and biased to exert pressure against the wall of said opening to retain said strips in said opening by friction, corresponding notches in said strips at both ends thereof, and a terminal wire held in at least one set of corresponding notches.

2. In combination, an insulating member having an opening therethrough of substantially rectangular cross-section, a pair of identical oppositely arranged metal strips passing through said opening, a shoulder on each strip, the shoulder of one strip contacting the surface of said member at one end of said opening and the shoulder of the other strip contacting said member at the remaining end of said opening, at least one of said strips being resilient and biased to exert spring pressure against the wall of said opening to retain said strips in said opening by friction, and means securing together said two strips against relative movement.

FRANK C. EBERT.
